UNITED STATES PATENT OFFICE

CHARLES V. MCINTIRE, OF EAST ORANGE, NEW JERSEY, ASSIGNOR TO CONSOLIDATION COAL PRODUCTS COMPANY, OF WILMINGTON, DELAWARE, A CORPORATION OF DELAWARE

RETORT FURNACE

Application filed August 20, 1925. Serial No. 51,523.

My present invention relates to retort furnaces and particularly to retort furnaces of the type of my prior Patent No. 1,457,083. A characteristic feature of the retort furnace of 5 my prior patent is the formation of a heat transmitting portion of the retort wall of metal sections shaped and disposed to form a segment of a circumferentially corrugated cylinder, and the primary object of the present invention is to provide improvements in 10 the form and disposition of such retort wall forming sections. More specific objects of the invention are to simplify the form and arrangement of the sections, and particularly 15 the provisions for minimizing gas leakage through the joints. Another object of the invention is to facilitate the replacement of metal wall sections when this becomes necessary.

20 The various features of novelty which characterize my invention are pointed out with particularity in the claims annexed to and forming a part of this specification. For a better understanding of the invention, however, its advantages and specific objects attained with its use, reference should be had to the accompanying drawings and descriptive matter in which I have illustrated and described preferred embodiments of my invention.

Of the drawings:

Fig. 1 is a longitudinal section on the broken line 1—1 of Fig. 2;

Fig. 2 is a transverse section on the line 35 2—2 of Fig. 1;

Fig. 3 is an enlarged partial section on the line 3—3 of Fig. 2 with parts broken away and in section;

Fig. 4 is a partial section on the line 4—4 of Fig. 2 and Fig. 3; and

Fig. 5 is a transverse section illustrating a modified form of retort structure;

Fig. 6 is a transverse section illustrating another modification;

Fig. 7 is an enlarged partial section on the line 7—7 of Fig. 6; and

Fig. 8 is an enlarged view partly in section on the line 8—8 of Fig. 6.

The retort A shown in Figs. 1, 2, 3, and 4, 50 is horizontally disposed, though its axis need

not be exactly horizontal, and has a curved bottom wall formed of metal sections B shaped to provide circumferentially extending internal and external grooves b and b', respectively. The metal sections B rest upon a bed or retort housing wall C formed of fire bricks, and which has its upper or inner cylindrical surface formed with recesses or pockets C' which unite with the grooves b' to form a plurality of undulating heating gas flues extending longitudinally of the kiln from heating gas inlet ports C² at the charge inlet end of the kiln, to heating gas outlet ports C³ at the discharge end of the kiln. As shown there are two of these longitudinal flues at each side of a longitudinal row of 60 uprising projections C⁵ from the wall C located beneath the retort axis. Each projection C⁵ enters a corresponding groove b' and separates the latter into two sections one at each side of the vertical plane including the retort axis. The heating gas inlet ports C² receive heating gases from the combustion chamber C⁴ which is provided, as shown, with burner inlets i, to which fuel gas is supplied by pipe connections i', and air for combustion is supplied by pipe connections i². The heating gas outlet ports C³ are connected to an off-take flue C⁶ running to a stack or other draft creating device (not shown).

The metal sections B are each trough shaped in cross section with one side edge shaped to form a tongue B' and with the other side edge reversely turned to provide a channel B² receiving the tongue B' of an adjacent section. The sections B are arranged in end to end pairs, the joints between the abutting end edges B³ of which are overlapped by the fire brick projections C⁵. At 85 its upper end each section B is formed with transverse projections B⁴ and B⁵, the outer edges of which bear against the inner side of the curved wall C, and which unite to close the upper ends of the grooves b'. Each projection B⁴ comprises a portion lying in the same plane with and really forming an extension of the adjacent section of the corresponding side edge tongue B', and each projection B⁵ is shaped to form an extension of 90 the corresponding groove B² to receive the 95

tongue portion of the projection B^4 of the adjacent section.

As in my prior patent, provisions are made for holding the end to end sections snugly against one another and against the wall C , while at the same time permitting the necessary freedom for relative expansion and contraction. The provisions shown for this purpose comprise levers D extending through a wall portion C^{10} of the retort housing above the upper edges of the wall C and each pivotally connected to the adjacent end of the corresponding section B which is provided with a yoke lug B^6 for the purpose. The outer end of each lever D is acted upon by a spring D' to apply a downwardly acting pressure to the upper end of the corresponding wall section B . The sections B may be made of cast iron, or preferably may be cast of one of the more highly refractory metallic alloys now coming into use for furnace and other high temperature work.

With the described construction, the joints between the different sections B can be luted with clay or other luting material if and when this becomes necessary, and in practice, of course, are covered and sealed in large part by the material treated in the retort. The sealing by the material working through the retort is especially effective in the intended use of the retort for the low temperature distillation of coal, because the coal in the retort adjacent its charging end, where the heating gas temperatures are the highest and relative expansion of the parts is correspondingly large, is largely in a molten or semi-molten condition.

The luting of the joints and the replacement of sections B which fail in operation are relatively simple and easy operations when the retort is out of service since the operations can then be carried on from the interior of the retort and the joints to be luted and the sections to be replaced are then readily accessible. In the use of a retort of the character specified for low temperature distillation of coal, it is usual to interrupt the retort for cleaning and inspection every three weeks or so. To facilitate inspection, cleaning and repairs, the retort is advantageously provided as shown with a removable top section or cover E which can be lifted off by an overhead traveling crane or like mechanism when the retort is closed down. The retort cover E normally rests on the upper edges of the housing wall portion C^{10} at the side of the retort and the adjacent end portions of the retort housing, and may be detachably secured in place by bolts E^5 .

The material to be treated is charged into the retort by a suitable feeding device F and the semi-coke is discharged at the opposite end of the retort through a suitably valved outlet connection G . The material is agitated in the retort and worked longitudinally

through the latter from the inlet end of the retort to the outlet G by an oscillating stirrer which advantageously is of the type disclosed in my prior Patent No. 1,479,827, granted January 8, 1924, comprising a power actuated oscillating shaft H which is co-axial with the corrugation grooves b . As in my last mentioned patent, the shaft H carries a set of arms H' which sweep through alternate grooves b , while the intermediate grooves b are swept by a corresponding set of arms H^2 which alternate, longitudinally of the shaft, with the arms H' , and are arranged in a row angularly displaced about the axis of the shaft from the row of arms H' . Cooperating with the arms H' and H^2 are stationary arms or vanes E' and E^2 . In accordance with the present invention the arms E' and E^2 are secured to the removable retort top E . The arms E' are in the same plane as the stirrer arms H^2 , and the arms E^2 are in the same plane as the stirrer arms H' . The shaft H is rotatable in the counter-clockwise direction for about 180° from the position shown in Fig. 2 and in the clockwise direction from the position shown in Fig. 2 for about 90° . As the shaft H is oscillated through the described range of movement, the arms E' remove material from the sides of the arms H' , and the arms E^2 remove material from the sides of the stirrer arms H^2 . The mounting of the arms E' and E^2 on the cover E obviously facilitates the inspection and repair of the retort when the cover E is removed. The retort is formed with a suitable gas take-off connection I , which, as shown, leads from the removable cover E , and comprises piping which can be easily opened to permit the removal of the cover E .

The improvements in retort wall construction disclosed herein are equally useful whether the general direction of flow of the heating gases is longitudinal of the retort as in the construction shown in Figs. 1 and 2, or is circumferential of the retort as shown in Fig. 5. The retort body CA of Fig. 5 differs from the retort body C of Figs. 1 and 2 in that pockets C' are omitted, and a single longitudinal off-take or stack connection flue C^{13} is provided. The flue C^{13} is connected by ports C^{12} at opposite sides of the masonry projections C^5 to the flue channels b' . In Fig. 5, fuel and air for its combustion is supplied to the flues b' at their upper ends through channels C^{11} in the masonry CA , and supply connections I^{10} to those channels.

Instead of metal wall forming sections with integral portions for closing the upper ends of the grooves B' as are shown in the constructions previously described, I may advantageously employ a construction as shown in Figs. 6, 7, and 8 in which separate end closing members M are provided. In this construction the body portions of the trough shaped wall forming sections BA employed,

are similar in transverse section to the members B first described. Each section BA is formed at its upper end with an axially extending slot B¹⁰ formed in the bottom of the trough portion of the member, and receiving the corresponding side flanges of a corresponding pair of end members M. Each end member M has an inner portion of inverted trough shape which fits over the meeting side edges of an adjacent pair of sections BA and has lips M' at its lower edges which extend through the slots B¹⁰ of the two sections BA into grooves C¹⁵ formed in the subjacent masonry bed CB. The latter, except as it is modified to co-operate with the end members M, may be similar either to the masonry bed C of Figs. 1 and 2, or to the masonry bed CA of Fig. 5. Each groove C¹⁵ is bifurcated at its upper end, each bifurcation communicating with a transverse groove C¹⁶ in the masonry which also communicates with the bifurcation of the groove C¹⁵ receiving the other side edge of the same member M. The outer portion of each end member is in the form of a box triangular in cross section with the bottom wall M² thereof terminating at its inner end in a transverse flange portion M³ which enters the corresponding groove C¹⁶ and merges into the lower portions of the corresponding side edge lips M'.

Each member M extends through an aperture formed for the purpose in a metallic portion C²⁰ of the housing wall of the retort, provided in this construction and extending between the masonry bed CB and the upper portion C¹⁰ of the retort housing. The outer portion of each member M forms a lever corresponding in general purpose to the lever D of the construction first described and similarly acted upon by a spring D'. The action of the springs D' on the lever ends M⁵ of the members M causes the latter to apply pressure to the upper end of the sections BA tending to hold the latter against their seats on the bed CB, and to maintain closed joints between the sections BA abutting end to end at the bottom of the retort, as the members BA expand and contract with changes in their temperatures.

The outer end of the triangular box-like portion of each member M is closed by a part N preferably made removable and formed with an inspection opening N' normally sealed by a suitable plug (not shown). Conditions inside the various flue spaces b' may be observed through the inspection openings N'. The joints between each member M and the two sections BA with which it cooperates, and also the joints between the lips M' and flange M³ and the adjacent walls of the grooves C¹⁵ and C¹⁶ may be sealed with fire clay or other luting material through the corresponding inspection opening N', though preferably the part N is removed to facilitate such luting when it becomes necessary.

The members M and N are preferably shaped, as shown, to provide a space for fire clay or other luting material for sealing the joints between them, and similarly each member M and the member C²⁰ are relatively shaped to provide a space for joint sealing or luting material.

While in accordance with the provisions of the statutes, I have illustrated and described the best form of embodiment of my invention now known to me, it will be apparent to those skilled in the art that changes may be made in the form of the apparatus disclosed without departing from the spirit of my invention as set forth in the appended claims, and that in some cases certain features of my invention may be used to advantage without a corresponding use of other features.

Having now described my invention, what I claim as new and desire to secure by Letters Patent is:

1. A corrugated retort wall formed of arc-shaped metallic sections trough shaped in transverse section and arranged side by side with the adjacent side edges of adjacent sections shaped to form a tongue and groove joint for connecting said sections.

2. A horizontal retort comprising a corrugated retort wall formed of side by side arc-shaped metallic sections trough shaped in transverse section, the side edges of adjacent sections forming overlapping joints, and provisions for sealing said overlapping joints.

3. A retort comprising a bottom part of refractory material having a concave upper surface and a metallic lining for said surface formed of side by side arc-shaped sections, trough shaped in transverse section and provided at one end with transverse web portions, the web portions at the corresponding ends of adjacent sections uniting to close the ends of the channels formed between the adjacent sides of adjacent sections and said concave surface.

4. A horizontal retort comprising a bottom part of refractory material having a concave upper surface and a metallic lining for said surface formed of side by side arc-shaped sections each trough shaped in transverse section and provided at one end with transverse web portions, said web portions uniting with the web portions at the corresponding ends of adjacent sections to close the corresponding ends of the channels formed between the adjacent sides of adjacent sections and said concave surface.

5. A horizontal retort comprising a bottom part of refractory material having a concave upper surface and having a row of parts having tapered sides and projecting upwardly from said surface, and a metallic lining for said surface formed of arc-shaped sections trough shaped in transverse section arranged side by side with the sides of said

sections fitting against the tapered sides of said parts whereby the arc-shaped channels formed by the adjacent sides of adjacent sections and said concave surface are closed by said parts.

5 6. A horizontal retort comprising a bottom part of refractory material having a concave upper surface with a row of refractory parts projecting upward therefrom and a metallic lining for said surface comprising two rows of arc-shaped circumferentially extending metallic sections each trough shaped in transverse section and with the sections in one row arranged end to end with the sections in the other row and with the joints between the abutting ends of the sections closed at the under sides of the sections by the projecting refractory parts.

10 7. A horizontal retort substantially circular in vertical cross section comprising a bottom part and a semi-cylindrical removable upper part, an oscillatable charge stirring member comprising a shaft axially mounted in said retort and provided with a pair of 15 angularly spaced radial arms, and separate cleaning devices for each of said arms carried by said removable upper part.

20 8. A horizontal retort comprising a bottom part of refractory material having a concave upper surface and a metallic lining for 25 said surface formed of arc-shaped sections arranged side by side, said surface being formed with depressions which cooperate with the circumferential grooves formed at the outer side of said lining to provide flues extending longitudinally of the retort, and means for supplying heating gases to the flues adjacent one end of the retort, and for withdrawing the heating gases at the opposite 30 end of the retort.

35 Signed at Fairmont, in the county of Marion and State of West Virginia this seventeenth day of August, A. D. 1925.
